Attorney

UNITED STATES PATENT OFFICE.

MALLE LITTLE RUSSELL, OF PHILADELPHIA, PENNSYLVANIA.

GARMENT SUPPORTER.

1,405,445.

Specification of Letters Patent.

Patented Feb. 7, 1922.

Application filed April 5, 1921. Serial No. 458,799.

To all whom it may concern:

Be it known that I, MALLE LITTLE RUSSELL, a citizen of the United States, residing at Philadelphia, in the county of Philadelphia and State of Pennsylvania, have invented certain new and useful Improvements in Garment Supporters, of which the following is a specification.

This invention relates to garment supporters, and more particularly to an improvement in skirt and waist holders, such as is shown in my prior Patent No. 757,756, dated April 19, 1904.

In the said prior patent, I have disclosed and claimed a garment holder for holding down the back portion of a waist, and supporting a skirt. The invention comprises a suitable frame having a plurality of oppositely arranged prongs adapted to be secured to the waist and skirt respectively, to maintain them in proper position.

In the present invention, I have provided a device of this character, having oppositely arranged prongs arranged relatively close to the surface of the body portion and adapted to be received in the waist and skirt, respectively, as in the former construction. In addition, I further provide oppositely arranged prongs disposed at right angles to the first named prongs and positioned further from the body portion, whereby the first named prongs may be first secured in the waist and skirt and the second named prongs then secured to either of the garments to insure retention of the garment holder in position.

In the accompanying drawings, I have shown one embodiment of the invention. In this showing:

Figure 1 is a rear elevation of one form of the invention.

Figure 2 is an end elevation thereof,

Figure 3 is a detail sectional view on line 3-3 of Figure 1, and,

Figure 4 is a detail perspective view of one of the auxiliary prongs.

Referring to the drawings, the reference numeral 1 designates the body portion of the garment holder which may be made of any suitable material and provided with ornamentation, if desired. Any of the noble metals may be employed where an expensive article of jewelry is to be produced, or baser metals may be employed, and provided with suitable covering of noble metal, if desired.

As shown, the body portion may be provided

with a depressed central portion 2, for the reception of a stone 3, or other setting.

The main fasteners comprise a pair of oppositely disposed U-shaped prongs 4, suitably secured to the body portion of the device, as at 5. As shown, the base of the U may be soldered to the body portion. The arms 6 are suitably curved to permit the device to be readily applied to the garment. These arms are arranged comparatively close to the body portion, whereby the main fasteners may be secured to the waist and skirt, respectively, as in my prior patent.

In the present invention, I provide a pair of auxiliary fasteners, arranged at right angles to the main fasteners. As shown, the auxiliary fastener comprises a pair of curved arms 7, having pointed ends 8. The rear of the arm is looped, as at 9, to space it a considerable distance from the body portion, and is received in a tubular sleeve 10, formed in a plate 11, secured to the body portion in any suitable manner.

When the device is to be applied, the main fasteners are first secured without interference by the auxiliary fasteners, due to their spaced position, and the device is then moved a slight distance at right angles to secure the auxiliary fasteners to the garment.

It will be apparent that with the four fasteners arranged at right angles to each other, the device is unlikely to become displaced.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A garment holder comprising a body portion, main fasteners arranged adjacent the top and bottom thereof, and provided with prongs projecting toward the center, and auxiliary fasteners arranged adjacent each side of the body portion and provided with prongs projecting toward the center, the prongs of the auxiliary fasteners being spaced from the body portion a greater distance than the prongs of the main fasteners.

2. A garment holder comprising a body portion, main fasteners arranged adjacent the top and bottom thereof, said main fasten-

ers comprising substantially U-shaped members, the base of the U-shaped member being secured to the body portion and the arms thereof being curved to slightly space the 5 fastener from the body portion, the ends of said arms being pointed, and auxiliary fasteners arranged adjacent the edge of the body portion and intermediate said main fasteners, each of said auxiliary fasteners 10 comprising a plate having a sleeve formed on each side thereof, and a fastening member secured in each of said sleeves, said fastening member comprising a piece of wire

having one end arranged in the sleeve, the intermediate portion thereof being looped 15 and the other end arranged over the sleeve and pointed, the pointed ends of the auxiliary fasteners being spaced a greater distance from the body portion than the pointed ends of the main fasteners.

In testimony whereof I affix my signature in presence of two witnesses:

MALLE LITTLE RUSSELL.

Witnesses:

M. O. BANNING,
ERNEST E. CONRAD.
